UNITED STATES PATENT OFFICE.

WILLIAM M. BLECKER, OF CANTON, OHIO, ASSIGNOR TO EDWARD A. LANGENBACH,
OF CANTON, OHIO.

AUTOMATIC SHEET SEPARATOR.

Application filed June 3, 1926. Serial No. 113,590.

The invention relates to apparatus for separating doubled or packed sheets from each other in sheet rolling operations.

The objects of the present improvement 5 are to provide automatic means for separating a pair or a pack of sheets from each other at a desired stage in a sheet rolling process.

These objects are attained by the use of 10 a construction and arrangement which may be described in general terms as including a plurality of sets of driven feed rolls having staggered nips for receiving a pair or pack of stuck sheets, and for reversely bending 15 the same to slide the sheets on each other and loosen the same, one or more sets of driven exit rolls for discharging separated sheets from the apparatus, and intermediate the feed and exit rolls, one or more adjustable 20 knives for separating the sheets, and guides for properly positioning the sheets in their passage from the feed rolls to the knives and from the knives to the exit rolls.

Several forms of the invention are illus- 25 trated in the accompanying drawings forming part hereof, in which—

Figure 1 is a longitudinal axial vertical cross section of one form of the invention for automatically separating sheet packs;

Fig. 2, a side elevation thereof;

Fig. 3, a longitudinal axial vertical cross section of another form of the invention for separating sheet pairs; and

Fig. 4, a side elevation thereof.

Similar numerals refer to similar parts throughout the drawings.

Referring to Figs. 1 and 2, a plurality of sets of driven feed rolls 10 and 10' are suitably journaled in a pair of side frames 11, the nips 12 of successive sets of the feed rolls being staggered with respect to each other, and preferably so staggered that the nips 12 of the first, third and fifth sets of feed rolls are in horizontal alignment with the opening 13^a between horizontal entrance guide plates 13 and 13', and the nips of the second and fourth sets of feed rolls being horizontally aligned with each other and below the aligned nips of the first, third and fifth sets.

By this staggered arrangement of the nips of the successive sets of feed rolls, a sheet pack passing therethrough is subject to a succession of reverse bends, setting up forces causing the separate stuck sheets to 55 slide upon each other and to open fan-wise the separate sheets at the advancing end of the pack.

Longitudinally spaced from the feed rolls, a pair of driven exit rolls 14 and 14' is suitably journaled in the frames 11 for discharging separated sheets from the apparatus, the nip 15 of the exit rolls being preferably in horizontal alignment with the opening 13^a between the entrance guide 65 plates 13 and 13'.

Intermediate the feed and exit rolls, and relatively close to the feed rolls, a plurality of transversely extending and vertically spaced hardened separating knives 16 are 70 adjustably mounted at their ends in the frames 11 and are provided with sharpened transverse edges 17 directed towards the feed rolls.

These separating knives are preferably 75 mounted between upper and lower transversely extending formed guide plates 18 and 18', for directing to the exit rolls the sheets fed from the feed rolls and through the transverse openings 16' and 16'' between 80 the guide plates and knives and between the knives respectively.

In operation the apparatus may be set up in a line of equipment as for continuous sheet rolling, and successive sheet packs P, 85 one of which is shown passing through the apparatus in Figs. 1 and 2, may be fed through the automatic separator for separating the individual sheets S of the pack from each other.

The advancing front end 19 of the pack illustrated in Fig. 1, has entered the apparatus through the horizontal opening 13^a between the entrance guide plates 13 and 13', and the staggered feed rolls have advanced 90 the pack through their staggered nips, thereby reversely bending the pack and tending to cause the separate sheets to slide upon each other and to open fan-wise the advancing ends of the separate sheets of 100

the pack, and the forward ends of the separate sheets have been advanced through the openings 16' and 16'' between the guides 18 and 18' and adjacent knives, and between 5 the intermediate knives 16, and the pack has been further advanced until its end 19 has been gripped by the exit rolls 14 and 14' which further draws the pack of separated sheets through the knife openings and dis- 10 charges the separated pack from the machine to the next piece of apparatus in the line.

The modified form of the apparatus illustrated in Fig. 3, is similar to the form 15 heretofore described, but is particularly adapted for the separation of sheet pairs, and includes a plurality of sets of driven feed rolls 10 and 10', suitably journaled in a pair of side frames 11, the nips 12^a of successive sets of the feed rolls being staggered with respect to each other, and preferably so staggered that the nips 12^a of the first, third and fifth sets of feed rolls are in horizontal alignment with the opening 20 13^b between horizontal entrance guide plates 13 and 13', and the nips of the second and fourth sets of feed rolls being horizontally aligned with each other and below the aligned nips of the first, third and fifth sets. 25 By this staggered arrangement of the nips of the successive sets of feed rolls, a pair of sheets passing therethrough is subject to a succession of reverse bends, setting up forces causing the separate stuck sheets 30 to slide upon each other and to open fan-wise the separate sheets at the advancing end of the pair.

Longitudinally spaced from the feed rolls, two pairs of driven exit rolls 14^a and 14'^a 40 preferably in vertical alignment with each other, are suitably journaled in the frames 11 for discharging separated sheets from the apparatus, the nips 15 of the exit rolls being preferably spaced at equal distances from 45 the horizontal axis of the machine passing through the horizontal entrance opening 13^a.

Intermediate the feed and exit roll, and relatively close to the feed rolls, a trans- 50 versely extending hardened separating knife 16 is adjustably mounted at its ends in the frame 11 and is provided with a sharpened transverse edge 17 directed towards the feed rolls.

The separating knife 16 is preferably 55 mounted between upper and lower transversely extending and vertically inclined outer guide plates 18^a and 18'^a, cooperating with inner plates 18^b and 18'^b for directing 60 to the exit rolls the sheets fed from the feed rolls and on each side of the separating knife.

In operation this form of the apparatus 65 may be set up in a line of equipment as for continuous sheet rolling, and successive

sheet pairs P', one of which is shown passing through the apparatus in Figs. 3 and 4, may be fed through the automatic separator for separating the individual sheets S of the pair from each other.

The advancing front ends of the pair of sheets illustrated in Fig. 3 have entered the apparatus through the horizontal opening 13^b between the entrance guide plates 13 and 13' and the staggered feed rolls have 70 advanced the pair through the staggered nips, thereby reversely bending the pair and tending to cause the separate sheets to slide upon each other and to open fan-wise the advancing ends of the separate sheets of 80 the pair, and the forward ends of the separate sheets have advanced through the openings 16' between the guides 18 and 18' and the knife 16, and the pair has been further advanced until the ends of each 85 sheet of the pair have been gripped by one of the pairs of exit rolls 14^a and 14'^a which further draw the pair of separated sheets through the knife openings and discharge the separated pair of sheets from the machine to the next piece of apparatus in the line.

I claim—

1. Sheet separating apparatus including a plurality of sets of driven feed rolls, the nips of the separate sets being staggered with respect to each other, a set of driven exit rolls spaced from the feed rolls, and a separating knife intermediate the feed and exit rolls.

2. Sheet separating apparatus including a plurality of sets of driven feed rolls, the nips of the separate sets being staggered with respect to each other, a set of driven exit rolls spaced from the feed rolls, a separating knife intermediate the feed and exit rolls, and guides adjacent the separating knife for directing sheets from the feed rolls to the exit rolls.

3. Sheet separating apparatus including a plurality of sets of driven feed rolls, the nips of the separate sets being staggered with respect to each other, a set of driven exit rolls spaced from the feed rolls, and a plurality of separating knives intermediate the feed and exit rolls.

4. Sheet separating apparatus including a plurality of sets of driven feed rolls, the nips of the separate sets being staggered with respect to each other, a set of driven exit rolls spaced from the feed rolls, a plurality of separating knives intermediate the feed and exit rolls, and guides adjacent the knives for directing sheets from the feed rolls to the exit rolls.

5. Sheet separating apparatus including a plurality of sets of driven feed rolls, the nips of the separate sets being staggered with respect to each other, a plurality of sets of driven exit rolls spaced from the feed

rolls, and a separating knife intermediate the feed and exit rolls.

6. Sheet separating apparatus including a plurality of sets of driven feed rolls, the 5 nips of the separate sets being staggered with respect to each other, a plurality of sets of driven exit rolls spaced from the feed rolls, a separating knife intermediate the feed and exit rolls, and guides adjacent the knife for directing sheets from the feed rolls to the exit rolls. 10

In testimony that I claim the above, I have hereunto subscribed my name.

WILLIAM M. BLECKER.
